CLAIM

The ornamental design for a crock, as shown and described.

DESCRIPTION

FIG. 1 is a perspective view of a crock showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof; and,

FIG. 9 is a cross section view showing a section taken along line 9-9 of FIG. 6.

The evenly dashed broken lines depict portions of the crock that form no part of the claimed design.

The dash-dot broken lines are for defining the bounds of the claimed design only and form no part of the claimed design.

1 Claim, 9 Drawing Sheets
